UNITED STATES PATENT OFFICE.

THEODORE R. TREIBER, OF CHICAGO, ILLINOIS, ASSIGNOR, BY MESNE ASSIGNMENTS,
TO J. C. McFARLAND COMPANY, A CORPORATION OF ILLINOIS.

POCKET-BILLIARD TABLE.

1,367,441.

Specification of Letters Patent.

Patented Feb. 1, 1921.

Original application filed May 3, 1919, Serial No. 294,433. Divided and this application filed October 13, 1919. Serial No. 330,302.

To all whom it may concern:

Be it known that I, THEODORE R. TREIBER, a citizen of the United States, residing at Chicago, in the county of Cook and State of Illinois, have invented a certain new and useful Improvement in Pocket-Billiard Tables, of which the following is a full, clear, concise, and exact description, reference being had to the accompanying drawings, forming a part of this specification.

My invention relates to pocket billiard tables and has particular relation to the ball return devices thereof, though certain features of the invention are not limited to this use alone.

One of the features of the invention relates to a novel design of ball gullies for pocket billiard tables and the like which prevents balls moving in the gullies from the various pockets from clogging, which permits of gullies which are gradually and uniformly inclined, which permits of a form of gullies allowing a short direct passage of balls therethrough to the discharge points thereof, and which is well adapted to a form of ball rack at one end of the table which maintains the balls in separated relation corresponding to the ball pockets from which they come. A supplemental feature relates to the arrangement of this type of gullies and a ball rack of the above described type, the arrangement being such that the combination is well adapted to be installed in a pocket billiard table.

Another feature relates to a ball rack construction which is adapted to be placed at one side of the table, which is well adapted to operate with gullies of the above described character and which is of non-clogging character in the discharge of the balls therefrom into the usual ball basket.

Another feature relates to a mechanism adapted to a ball rack of the above described character which includes movable means for maintaining the balls in the several racks and which may be moved to open position, and which when in open position forms a guide on one side of a vertical space for the balls as they drop from their respective racks through said vertical space. A supplemental feature to this relates to the provision of a ball rack of the above character which includes two series of ball racks extending in

the same direction on opposite sides of a vertical space in combination with two of the 55 movable means above mentioned and a connection therebetween to cause the same to move to and from closed positions in synchronism. The ball rack construction is particularly adapted to a game table having a 60 ball gully design as above mentioned.

The above features and certain other features hereinafter appearing are embodied in the preferred form of my invention, herein-after fully described and illustrated in the 65 accompanying drawings, and are effected by certain novel constructions, combinations and arrangements of parts particularly pointed out in the claims.

In the said drawings—

Figure 1 is a view in front elevation of a pocket billiard table embodying the features of my invention.

Fig. 2 is a sectional view of the same in side elevation on the line 2—2 of Fig. 1.

Fig. 3 is a top plan view of the same with the cushion rails and slates removed.

Fig. 4 is an enlarged partial sectional view in front elevation on the line 4—4 of Fig. 2.

Fig. 5 is an enlarged partial sectional view 80 in oblique plan elevation on the line 5—5 of Fig. 2.

Like characters of reference indicate like parts in the various views.

In the drawings 1 indicates the frame of 85 the table which is of inverted rectangular frusto-pyramidal shape which is supported by downwardly extending legs 2 disposed at the corners of the frame and at the centers of the long sides thereof. The frame of the 90 table as shown is of sheet metal and a detailed description of the same is unnecessary here. However, the structure of the frame as shown is fully described and claimed in my U. S. application Serial No. 294,433, 95 filed by me May 3, 1919, for improvement in game tables, of which this application is a division.

As is usual slates 3 are mounted on top of the frame and cushion rails 4 are secured to the edges of the slates. These cushion rails and attached cushions 5 are cut out as is usual at the corners and at the centers of the long sides of the table to form ball pockets, and the upper portions of the sides 100 of the frame and supporting structure are

cut away below their ball pockets as designated at 6, see Figs. 2 and 3, to allow the balls to drop down upon the upper ends of gullies 37 which rest upon and are secured 5 to flanges 15 secured to the frame 1. An individual gully 37 is provided for each ball pocket and they are all inclined downwardly therefrom and extend to points at one side of the table, preferably one of the short 10 sides of the same as shown, as designated at 39. This arrangement of an individual gully for each pocket inclined downwardly from the pockets to points at one side of the table prevents the balls from clogging in 15 the gullies under the table as is often the case where the gullies lead into one another. The gullies are arranged correspondingly with the ball pockets and so that the gully of the pocket farthest distant from the discharge point of the gullies is the lowest at 20 the discharge points of the gullies. This arrangement permits of gullies which are gradually and uniformly inclined and permits the gullies to lead directly to their discharge points. This arrangement also 25 adapts the gullies to the ball rack construction hereinafter described by permitting the discharge points of the gullies to be disposed in superposed relation adjacent the side of 30 the table along which the respective ball pockets are arranged, as is shown in the drawings, without interfering with the arrangement of the gullies. The gullies leading from the pockets nearest adjacent the 35 discharge ends of the gullies are substantially U-shaped to extend the lower ends thereof in the same direction as the discharge ends of the lower gullies where, as is shown, all the gullies are disposed within 40 the inclosure of the sides of the table. The center portions of the longer gullies are supported by metal straps 40 extending underneath the respective gullies with their middle portions and having their ends secured 45 to respective cross girders 20 of the frame, and the center portions of the U-shaped gullies, above described, are supported by respective brackets 41 secured to and extending from the inner face of the adjacent 50 side of the frame 1. The lower end of each gully extends to a respective opening 42 formed in the adjacent side of the frame and the metal displaced from these openings is turned inwardly from the lower portion of 55 the opening, as designated at 43, and the adjacent end of the respective gully rests thereon and is secured thereto.

Secured to the outer surface of the side of the frame 1, in which openings are formed, 60 by brackets 44 is a series of ball racks 45 corresponding in number and superposed in the same relation as are the gullies. The openings 42 to which the several gullies 37 of each longitudinal side of the table lead 65 are disposed adjacent that side, and the cor-

responding ball racks extend in parallelism with the side to which they are secured toward the center of this side and are preferably inclined downwardly toward the same. The ball racks are thus disposed in 70 superposed relation corresponding to the superposed relation of the gullies, each of which is adapted to receive balls from one respective gully, whereby the ball pocket into which the balls dropped may be easily 75 ascertained by their position on the several ball racks.

Two series of ball racks are provided one for the gullies of each long side of the table and they are arranged close up to the adjacent side of the table for obvious reasons. The adjacent ends of these ball racks are spaced to allow the balls to fall vertically through said space, and the usual basket 46 is hung on a hook 47 secured to the frame 1 80 to catch the balls as they drop through said vertical space. These adjacent ends of the ball racks of the two series of ball racks are disposed in different horizontal planes, as 85 shown in Fig. 1, to prevent one ball from 90 one rack of one series entering the space between the two series of racks and meeting a ball entering this space from the corresponding rack of the other series and clogging. 95

The gullies 37 and ball racks 45 are similar in construction and the structures thereof are formed of sheet metal bent, see Fig. 4, to provide two parallel spaced upwardly facing channels 48 in which are secured rails 49, of rubber or other suitable material upon which the balls 50 run. The upper ends of the ball racks 45 are curved into the corresponding openings 42 to meet the ends of the respective gullies, and the gullies are curved at suitable points, see Fig. 3, and the sheet metal structure of the gullies and ball racks is extended upwardly of the rails on the outsides of these curves, as designated at 51, see Fig. 4, to prevent the 100 balls jumping off of the rails at the curves thereof. 105

A vertical guide rail 52 is provided for each series of balls, and is pivotally mounted on a vertical axle on brackets 53, secured to the adjacent side of the frame 1, adjacent the discharge ends of the ball racks 45. These rails are adapted, when in one position, to close the ends of the corresponding series of ball racks, and when in another position, to open 110 said ends and to form a vertical guide on one side of the aforementioned space between the adjacent ends of the ball racks for balls entering the same from said ends of the ball racks, the adjacent side of frame 1 forming a guide at the opposite side of said space. The upper ends of the axles of these vertical rails have intermeshing gears 54 secured thereon which cause the two vertical rails to move to and from their closed 115 120 125 130

positions in synchronism. An operating handle 55 is secured at the upper end of the axle of one of said guides to facilitate the operation of the same. A detent hook 56 is secured to one of the adjacent brackets 53 and is adapted to be engaged with the handle to maintain the rails in their closed positions. This construction provides a convenient and simple closing device which, 10 when in open position, serves as a vertical guide for the balls as they drop from the racks.

While I have herein shown and particularly described the preferred embodiment 15 of my invention I do not wish to be limited to the precise details of construction shown as changes may readily be made without departing from the spirit of my invention, but having thus described my invention I 20 claim as new and desire to secure by Letters-Patent the following:—

1. A game table including a plurality of individual ball gullies, each leading from a respective ball pocket of the table to super- 25 posed points at one side of the table, the gullies being arranged correspondingly with the ball pockets and so that the gully of the pocket farthest distant from the discharge point of the gullies is the lowest at 30 the discharge points of the gullies.

2. A game table including a plurality of individual ball gullies, each leading from a respective ball pocket of the table to super- 35 posed points at one side of the table, the gullies being arranged correspondingly with the ball pockets and so that the gully of the pocket farthest distant from the discharge point of the gullies is the lowest at the discharge points of the gullies, the gully of the 40 pocket nearest the discharge points being substantially U-shaped.

3. A game table having a plurality of ball pockets arranged along opposite sides of the table including a corresponding plurality 45 of individual ball gullies for each plurality of pockets, all of the ball gullies leading from a respective ball pocket to points at one of the other sides of the table, the ball gullies of each plurality of pockets leading 50 to superposed points at said other side adjacent the respective of said first mentioned sides and arranged correspondingly with the ball pockets and so that the gully of the pocket farthest distant from the discharge 55 point of the gullies is the lowest at the discharge points of the gullies, and a plurality of ball racks for each plurality of gullies arranged in similar superposed relation and adapted to receive balls from the respective 60 gullies, said pluralities of ball racks extending toward each other and discharging into a common vertical discharge opening.

4. A game table having a plurality of ball pockets arranged along opposite sides 65 of the table including a corresponding plu-

rality of individual ball gullies for each plurality of pockets, all of the ball gullies leading from a respective ball pocket to points at one of the other sides of the table, the ball gullies of each plurality of pockets 70 leading to superposed points at said other side adjacent the respective of said first mentioned sides and arranged correspondingly with the ball pockets and so that the gully of the pocket farthest distant from the 75 discharge point of the gullies is the lowest at the discharge points of the gullies, a plurality of ball racks for each plurality of gullies arranged in similar superposed relation and adapted to receive balls from the respective 80 gullies, said pluralities of ball racks extending toward each other and discharging into a common vertical discharge opening, and means for retaining balls on said ball racks adapted to be operated to allow balls to be 85 discharged therefrom into said discharge opening.

5. A ball rack including two series of parallel superposed ball racks, each series extending in the same direction, and the adjacent ends thereof being spaced to allow the balls to fall vertically through said space, these adjacent ends of the two series of racks being disposed in different horizontal planes to prevent one ball from one 95 rack of one series entering the space between the two series of racks and meeting a ball entering this space from the corresponding rack of the other series and clogging. 100

6. A ball rack including two series of parallel superposed ball racks, each series extending in the same direction, and the adjacent ends thereof being spaced to allow the balls to fall vertically through said 105 space, the ball racks in both series being inclined downwardly toward said space, said adjacent ends of the two series of ball racks being disposed in different horizontal planes to prevent one ball from one rack of one 110 series entering the space between the two series of racks and meeting a ball from the corresponding rack of the other series and clogging.

7. A ball rack including a plurality of 115 parallel superposed ball racks, the corresponding ends of said ball racks lying on one side of a vertical space; and a vertical rail movably mounted and adapted to close said ends of the racks when in one position 120 and to open said ends and to form a vertical guide on one side of said space for balls entering the same from said ends of the ball racks when in another position.

8. A ball rack including a plurality of 125 superposed ball racks, corresponding ends of said ball racks lying on one side of a vertical space; and a vertical rail pivotally mounted for swinging movement on a vertical axis and adapted to close said ends of 130

the racks when in one position and to open said ends and to form a vertical guide on one side of said space for balls entering the same from said ends of the ball racks when 5 in another position.

9. A ball rack including a plurality of superposed ball racks, corresponding ends of said ball racks lying on one side of a vertical space, said ball racks being inclined 10 downwardly toward said vertical space; and a vertical rail movably mounted and adapted to close said ends of the racks when in one position and to open said ends and to form a vertical guide on one side of said 15 space for balls entering the same from said ends when in another position.

10. A ball rack including two series of parallel superposed ball racks, each series extending in the same direction and the adjacent 20 ends thereof being spaced to allow the balls to fall vertically through said space; and a vertical rail for each series, each rail being movably mounted and adapted to close said adjacent ends of the respective series 25 of rails when in one position, said rails being adapted when in another position to open said ends of their respective series of racks and to form vertical guides on one side of said space.

11. A ball rack including two series of parallel superposed ball racks, each series extending in the same direction and the adjacent ends thereof being spaced to allow the balls to fall vertically through said 35 space, said ball racks being inclined downwardly toward said space; and a vertical rail for each series, each rail being movably mounted and adapted to close said adjacent 40 ends of the respective series of rails when in one position, said rails being adapted when

in another position to open said ends of their respective series of racks and to form vertical guides on one side of said space.

12. A ball rack including two series of parallel superposed ball racks, each series 45 extending in the same direction and the adjacent ends thereof being spaced to allow the balls to fall vertically through said space; a vertical rail for each series, each rail being movably mounted and adapted to close said 50 adjacent ends of the respective series of rails when in one position, said rails being adapted when in another position to open said ends of their respective series of racks to form vertical guides on one side of said 55 space; and connections between said vertical rails adapted to cause said rails to move to and from their closed positions in synchronism.

13. A ball rack including two series of parallel superposed ball racks, each series 60 extending in the same direction and the adjacent ends thereof being spaced to allow the balls to fall vertically through said space, said ball racks being inclined downwardly 65 toward said space; a vertical rail for each series, each rail being movably mounted and adapted to close said adjacent ends of the respective series of rails when in one position, said rails being adapted when in another position to open said ends of their respective 70 series of racks and to form vertical guides on one side of said space; and connections between said vertical rails adapted to cause said rails to move to and from their closed 75 positions in synchronism.

In witness whereof I hereunto affix my signature this 7th day of October, 1919.

THEODORE R. TREIBER.
